UNITED STATES PATENT OFFICE.

DAVID D. NOLLEY, OF WILSON, ASSIGNOR TO BENJAMIN H. TYSON, OF RALEIGH, NORTH CAROLINA.

DESIGN FOR A SEAL-LOCK HASP.

SPECIFICATION forming part of Design No. 23,801, dated November 13, 1894.

Application filed October 4, 1894. Serial No. 524,926. Term of patent 14 years.

To all whom it may concern:

Be it known that I, DAVID DANIEL NOLLEY, of Wilson, in the county of Wilson and State of North Carolina, have invented and produced a new and original Design for Seal-Lock Hasps; and I do hereby declare the following to be a full, clear, and exact description of the invention, such as will enable others skilled in the art to which it pertains to make and use it, reference being had to the accompanying drawing, which forms part of this specification.

My invention relates to designs for seal lock hasps, illustrated in the accompanying drawing which is a perspective view of the same.

A is the body portion of the hasp embodying my design, having at one end a configuration formed by the opening B with a lip depending from its upper wall and above the lip a laterally projecting lug D, having an opening E.

Having thus described my invention, what I desire to secure by Letters Patent is—

The design for seal lock hasp substantially as herein shown and described.

In testimony whereof I affix my signature in presence of two witnesses.

DAVID D. NOLLEY.
